UNITED STATES PATENT OFFICE.

THOMAS J. FAY, OF BROOKLYN, NEW YORK, ASSIGNOR, BY MESNE ASSIGNMENTS, TO THE STANDARD PARTS COMPANY, OF CLEVELAND, OHIO, A CORPORATION OF OHIO.

FRICITION-LEAF FOR SPRINGS.

1,319,214.

Specification of Letters Patent. Patented Oct. 21, 1919.

Application filed May 6, 1914. Serial No. 836,633.

To all whom it may concern:

Be it known that THOMAS J. FAY, a citizen of the United States, residing at Brooklyn, in the county of Kings and State of New York, have invented a certain new and useful Improvement in Friction-Leaves for Springs, of which the following is a full, clear, and exact description, reference being had to the accompanying drawings.

- 10 This invention relates to vehicle springs, and more particularly to springs that are equipped with what are known to the trade as "inserts", such inserts being interposed between the plates for various purposes. It 15 is the purpose of this invention to provide means, preferably in the form of such inserts, whereby great uniformity of friction may be maintained between the adjacent plates, the rusting of the plates prevented, 20 and noise attending the action of said plates eliminated. Further objects of the invention will appear hereinafter in connection with the detailed description.

In the drawing forming part hereof Figure 1 represents a side elevation of a spring, showing the same clamped at its central portion to a vehicle axle, the spring having inserts formed in accordance with my invention interposed between the plates thereof; and Fig. 2 is an enlarged detail in perspective of a part of the spring shown in the preceding figure.

Describing by reference characters the various parts illustrated in the drawing, 1 denotes the axle of a vehicle and 2, 3, 4, 5 and 6 the plates of a multi-leaf spring of the semi-elliptic type, the number of leaves being such as will suit the particular requirements of the installation. The spring 40 is shown as clamped at its middle portion to the seat 7 on top of the axle by means of the usual spring clips 8 and a short plate 9 resting on top of the main plate 2 of the spring. Between adjacent plates 2, 3, 4, 45 etc., there are interposed strips or ribbons 10 of fabric saturated with a non-movable material of gum-like consistency. This material is a mixture of beeswax and resinous gums, the beeswax and gums being mingled and applied in a hot or molten condition to the fabric, whereby the interstices of the fabric will be filled with this material of

gum-like consistency. In selecting the ingredients for the material with which the fabric is saturated, I employ beeswax because of its rust-preventing qualities and resinous gums because of their anti-lubricating qualities. 55

It will be readily understood that, with the interstices of the fabric filled with this material of gum-like consistency, the leaves will be prevented from rusting while a high and uniform friction will be opposed to the relative movements between the plates. Each ply or ribbon of fabric provides a 65 reservoir for the retention of the non-lubricating gum-like material. In practice, I prefer to use No. 14 duck for the fabric and, with fabric of this weight and thickness, interposed between the leaves of an ordinary 70 spring, the cumulative effect of these plies, under compression at the center of the spring, is to place the spring clips 8 under such constant tension as will prevent the nuts 8^a from loosening on the threaded ends 75 of the clips, thereby dispensing with the use of any locking devices for the nuts.

A further and very material advantage in connection with this invention resides in the fact that the inequalities in the surfaces 80 of the spring plates, which normally interfere with and even defeat the proper action of these plates, are rendered negligible owing to the interposed cushion of fabric which, being compressible, will conform 85 to these undulations or inequalities and equalize the resulting pressures.

Having thus described my invention, what I claim is:—

1. A spring comprising a plurality of plates having interposed therebetween fabric which is impregnated or saturated with rust-preventing and anti-lubricating material.
2. A spring comprising a plurality of plates having interposed therebetween fabric which is impregnated or saturated with anti-lubricating material.
3. A spring comprising a plurality of leaves, there being interposed between adjacent leaves a layer of fabric which is saturated with beeswax and resinous gums.
4. The combination, with a spring seat, of a spring comprising a plurality of plates

having interposed therebetween layers of fabric saturated with anti-lubricating and rust-preventing material, and clips extending around the central portion of the spring 5 and securing the same to the seat.

5. A spring comprising a plurality of plates having interposed therebetween a mixture of wax and a resinous substance whereby rust is prevented and a uniform

friction is created and maintained between 10 said plates.

In testimony whereof, I hereunto affix my signature in the presence of two witnesses.

THOS. J. FAY.
